FOOD TREATMENT AND/OR STORAGE APPARATUS

Arthur R. Dennington, East Orange, N. J., assignor to Westinghouse Electric & Manufacturing Company, East Pittsburgh, Pa., a corporation of Pennsylvania

Application January 26, 1940, Serial No. 315,707

20 Claims.

(CL 62—89)

This invention relates to the storage of foods and, more particularly, to improved apparatus for preserving, tenderizing and/or storing food or the like.

A principal object of my invention, generally considered, is the provision of refrigerating apparatus for efficiently maintaining food, and particularly meat, at a desired tenderizing and/or storage temperature while surrounded by an atmosphere of high humidity, preferably at the same time, avoiding the growth of mold and bacteria on such material during tenderizing or storage.

Another object of my invention is the provision of baffles, preferably extending longitudinally of the cooling pipes or coils and disposed between the top portion thereof and the ceiling or top wall of the refrigerator, in order to control the air circulation and provide for efficient cooling, while maintaining a desired high humidity.

A further object of my invention is the provision of a refrigerator having baffles between the ceiling and top edge of the cooling means, and deflectors projecting down from the ceiling and disposed at the proper angle to control the distribution of air through the cooling means.

Another object of my invention is the provision of deflectors in deep cooling coils to direct the air flow through the fins.

A still further object of my invention is the provision of a refrigerator with deflectors and/or baffles for controlling the flow of air over and through the cooling pipes, and fans for increasing the rate of flow of such air, said fans being desirably directed toward the baffles, preferably in a very nearly horizontal direction.

Another object of my invention is the provision of a refrigerator having fans and baffles or deflectors to move the air rapidly over the cooling pipes and thus re-evaporate moisture condensed on the cooling surfaces instead of allowing it to remain as frost or drip off and be lost down the drain.

A further object of my invention is the provision of a refrigerator with rapid absorption of heat from the air to the cooling coils by rapid movement of air therethrough, while maintaining gentle air movement over the food products.

Another object is the provision of a refrigerator which maintains a nearly constant temperature and high relative humidity under working conditions, even when the door is opened frequently.

An additional object of my invention is the provision of a refrigerator having baffles to con-

trol the flow of air therein, means for humidifying said air, and ultra-violet generators for minimizing the development of bacteria and mold, said generators being preferably disposed in a position to be swept over slowly by the circulating air.

Other objects and advantages of the invention, relating to the particular arrangement and construction of the various parts, will become apparent as the description proceeds.

In commercial refrigerators, of what is designated as the "walk-in" type, for the storage of perishable foods such as meats and vegetables, it is essential to keep the relative humidity of the air contained therein high, in order to prevent drying and withering of the stored materials.

Such an effect may be accomplished in new refrigerators by the proper design of the cooling coils, the application of the correct size of condensing unit, and the use of an efficient humidifier, but at considerable increase in initial cost.

Refrigerators which have been completed and are fitted with overhead cooling coils, or pipes having cooling fins extending therefrom, usually have insufficient cooling area to permit relative humidity of more than 70 to 75% which is too low for optimum conditions in the tenderization and/or preservation of meat and other food. Raising the temperature at which the refrigerator is operated by increasing the temperature of the refrigerating coils or pipes, is not enough of a change to give relative humidities of 85 to 95%, which are required.

Also as the temperature of the cooling coils approaches the temperature of the surrounding air, which is a necessary condition for high humidity, the air circulation due to gravity decreases, thus tending to produce stagnation. It is, therefore, essential to force rapid movement of the air over the cooling coils, if the moisture deposited on the coils is to be re-evaporated into the air and the relative humidity maintained at about 90% or more.

Other changes therefore, are required, and these which comprise my invention and give a new and desired result, will now be described.

In order to secure high relative humidity, it is necessary to operate the cooling coils or pipes at temperatures which are not much below the freezing point at any time, and which are above the freezing point long enough during the "off" cycle, or the period when the condensing unit is not operating, to completely melt off any frost or ice which may have formed while the machine was running.

With the ordinary arrangement of the cooling coils and bunkers, the convection currents through the coils are not sufficiently rapid, nor does all the circulating air pass through or between the coils or pipes in order to cool it to the required degree. These difficulties have been overcome, in accordance with my invention, by placing baffles between the inner top edge of the cooling coils or pipes and the ceiling or top wall of the refrigerator, supplemented, in some cases, by deflectors projecting down from the ceiling to distribute the air from fans placed in the warm air flue above the coils, and direct it toward the baffles, preferably in a nearly horizontal direction.

Referring to the drawing illustrating improved apparatus embodying my invention:

Figure 1 is a vertical sectional view of a refrigerator or meat-treating compartment employing my invention.

Figure 2 is a vertical sectional view of apparatus similar to that of Figure 1, but slightly modified.

Figure 3 is a vertical sectional view of apparatus similar to that of Figure 1, but involving another modification.

Figure 4 is a fragmentary view of apparatus, such as shown in Figure 2, but modified to include another layer of cooling coils or pipes, shown in end elevation.

Figure 5 is a chart showing the temperature and humidity control in a refrigerator embodying my invention, as compared with that in one lacking the inventive features.

Referring to the drawing in detail, like parts being designated by like reference characters, and first considering the embodiment of my invention illustrated in Figure 1, there is shown a refrigerator or meat-treating and storing box 11, comprising a room or compartment 12, provided with shelves, racks or other means 13, for supporting and storing meat 14, or other food. Hooks 15 may be provided for suspending large pieces or carcasses of meat.

As in the James Patent No. 2,169,081 of August 8, 1939, refrigerating coils or pipes 16 are shown disposed directly in the compartment 12. In the present embodiment these pipes have fins 17, extending therefrom for increasing the heat-absorbing capacity, in order to thereby augment the refrigerating effect obtained by their use. Any suitable means may be provided for circulating refrigerating fluid in said pipes.

In order to provide the desired humidity in the compartment 12, means are provided for circulating air over the cooling coils, which provide a greater area of moist surface than do the food products stored in the refrigerator. The cooling coils condense moisture from warm air entering the refrigerator and form a desirable source of moisture to keep the relative humidity so high that there is little loss of moisture from the food products. If air movement over the moist cooling surfaces is slow, the moisture on the pipes and fins accumulates in drops which fall into the drain and pass out of the box. Increasing the air flow through and around the cooling coils results in an increase in the amount of moisture returned to the air and retained by it, thus maintaining high relative humidity.

The relatively slower movement of air in the food compartment coupled with the fact that it has passed over the large moist surfaces of the cooling coils and is nearly saturated, results in minimum drying of the food product. As the forced circulation of the air is in the same direc-

tion as the natural convection currents, there is less tendency, than with a system in which forced air circulation is opposite to the direction of natural convection currents, for stagnation of air in parts of the refrigerator. The ideal conditions for the preservation of food are approached more nearly than heretofore, and by simplified methods.

In refrigerators carrying small amounts of meat, supplementary moist surfaces, designated by the reference characters 18 and 19, may be provided. Such supplemental moisture-supplying means, may, for the sake of simplicity, comprise pans of water from which project absorbent devices 21, which may be viscose sponges or other similar material for increasing the moisture distributing area. These supplementary humidifying devices are disposed so as to give off moisture to the air as it circulates. However, it will be understood that the principal source of moisture for the cooled air is the cooling surface itself and that any other humidifying means, or stored material, contributes only a small amount when my invention is utilized.

Bunker or drip pans, coil decks, or partitioning walls, 22 and 23, are shown disposed under the refrigerating pipes 16, and in the present embodiment slope down and toward one another, with outer baffling extensions 24 disposed vertically along the outer sides of the pipes, and define the bunker space. In order to cause the circulating air to pass directly between the coils or pipes 16, rather than completely thereabove, or eddying in top of the refrigerator, I provide baffles 25 and 26, desirably disposed diagonally, and extending from the ceiling 27 inwardly and downward to approximately the top of the refrigerating means 16-17. These baffles 25 and 26 may be augmented by the employment of one or more deflectors 28 and 29, extending from the ceiling 27 part way toward the refrigerating coils, or placed along the coils to separate thick from thin sections (Fig. 4), to aid in distributing the air uniformly therethrough. They may extend parallel to the adjacent baffle, as illustrated in Figure 1 or, in some instances, it may be desirable to turn some or all of them at an angle thereto, as indicated in Figure 3 by the reference character 29.

Although it may be sufficient to rely on a gravity circulation of air, as indicated by the arrows 31, yet I prefer to employ electric fans 32 and 33, desirably controlled by a switch 34, for augmenting the circulation of the air up at the sides of the box, and down through or between the cooling pipes 16, in order to get the maximum cooling and humidifying effects.

High relative humidity in a food storage compartment not only provides the advantages of reduced drying and discoloration of the food products and their maintenance in fresh condition, but also furnishes moisture conditions favorable to the development of bacteria and mold. These undesirable factors may be reduced or eliminated by means of sterilizing or sanitizing ultra-violet radiations in the region of 2500 Angstrom units, which radiations may be generated by apparatus which will now be disclosed.

Beneath the bunker space, or otherwise suitably disposed, are desirably positioned means 35, 36, 37 and 38 generating ultra-violet light having the major part of its radiations near 2500 A. U., or between 2500 and 3000 A. U., with a large proportion of the radiations between 2500 and 2800 A. U. with very little visible and infra-red radi-

ations, and hardly any radiations of wave lengths below 2500 A. U., thereby avoiding harmful effects and the generation of any substantial amount of ozone. This means desirably takes the form of one or more lamps, each of which is preferably constructed in accordance with the copending application of Robert F. James, Serial No. 734,620, filed July 11, 1934, and owned by the assignee of the present application. The operation of these lamps is desirably controlled by means of a switch 39.

In operation, air is desirably caused to circulate, not only by the natural gravitational tendency but also by power means, such as the fans 32 and 33, which force the air up at the sides of the compartment 12, over and between the cooling and humidifying pipes or coils 16, when the cooled and moistened air passes over the bunker pans 22 and 23, and is discharged diagonally downward and inward at the center of the box from whence it drops toward the floor and then repeats its circuit.

Referring now to the embodiment of my invention illustrated in Figure 2, there is shown a refrigerator or meat treating and storing device 11^a, comprising a room or compartment 12^a provided with means 13^a for supporting and storing meat 14^a, or other food. Hooks 15^a may be provided for suspending large pieces of meat, as illustrated.

Refrigerating and humidifying coils or pipes 16^a are shown disposed directly in the compartment 12^a. In the present embodiment, these pipes are arranged as one group rather than two, and have fins 17^a extending therefrom for increasing the heat-absorbing capacity.

Supplementary humidifying means may be provided, like those designated 21 in the preceding embodiment, if desired, especially if there is only a small amount of meat or other foods in storage.

A bunker pan or partitioning wall 22^a is shown disposed under the pipes 16^a and in the present embodiment it extends diagonally from near one side toward the other, with a baffling extension 24^a disposed vertically from the higher side of the bunker and along one outer side of the pipes 16^a.

In order to cause the circulating air to pass directly between the coils or pipes 16^a, rather than completely thereabove, I provide a baffle 25^a desirably disposed diagonally and extending from the ceiling 27^a downwardly and toward one side wall, to approximately the top of the refrigerating and humidifying means 16^a—17^a. The action of this baffle may be augmented by the employment of one or more deflectors 28^a and 29^a extending from the ceiling 27^a part way toward the refrigerating coils to aid in air distribution. As in the previous embodiment, the deflecting means may extend parallel to the baffle 25^a, as illustrated, or be disposed at an angle thereto, as indicated in Figure 3 by the reference character 28^c.

In the present embodiment I prefer, not to rely on a gravity circulation of air, as indicated by the arrows, and so may use an electric fan 32^a, desirably controlled by a switch 34^a for augmenting the circulation of the air up at the right side of the box and down through or between the cooling pipes, from whence it is discharged downwardly at the left side of the box, thereby getting maximum cooling, humidifying, and circulating effects.

I may dispose, directly beneath the bunker 75

pan 22^a, means 35^a and 36^a, generating ultra-violet light having a major part of its radiations near 2500 A. U., or between 2500 and 3000 A. U., with a large proportion of the radiations between 2500 and 2800 A. U., very little visible and infrared radiations, and hardly any radiations of wave lengths below 2500 A. U., thereby avoiding harmful effects and the generation of any substantial amount of ozone. Ultra-violet radiations in this region extend the time that food products may be kept in good condition in storage. If the bunker pan and associated cooling means 16^a are close to the meat racks 13^a or, in any event, in order to have the circulating air pass freely and gently over and around said generating means, the same may be disposed adjacent the side walls of the compartment 12^a, as illustrated, so that, for example, the generator 36^a lies in the upward stream of circulating air while the generator 35^a lies in the downward stream thereof.

The sterilizing action of the generators 35^a and 36^a may be supplemented by that of similar generators 37^a and 38^a disposed along the side walls, all of said generators being desirably controlled by a switch 39^a. These generators are desirably in the form of lamps, preferably constructed in accordance with the James application, Serial No. 734,620, previously referred to.

In operation, air is caused to circulate substantially as described in connection with the preceding embodiment and as indicated by the arrows.

Referring now to the embodiment of my invention illustrated in Figure 3, there is shown a refrigerator or meat treating and storing device 11^b, which may be identical with the device 11 of Figure 1, except that the bunker pans 22^b and 23^b are in the form of individual drip pans 41, 42, 43, 44, 45 and 46, rather than a single one extending completely beneath the bank, or each bank, of cooling means or pipes 16^b. In the present embodiment the ultra-violet generators 35^b, 36^b, 37^b and 38^b may be disposed with the first two beneath the drip pans 41, 42 and 43, and the last two beneath those designated 44, 45 and 46, or the generators 35^b and 38^b, may be placed on the side walls just below the drip pans, and the generators 36^b and 37^b on the ceiling, as illustrated, or only one pair may be employed, if found sufficient.

A further distinction, as compared with the embodiment of Figure 1, is that the deflector 29^c is shown disposed at an angle to the adjacent baffle 26^b, while the deflector 28^b is shown disposed parallel to the baffle 25^b, so that while the air from the fan 32^b is deflected transversely and diagonally downward with respect to the compartment 12^b, some of the air from the fan 33^b is deflected diagonally downward and diagonally transverse to the compartment 12^b. It will, however, be understood that the deflectors in any of the compartments may be disposed at angles where they are found by trial to get the best results, or may be placed along the coil so as to deflect the air through the thicker parts thereof. The ultra-violet generators may also be arranged in any compartment, either as shown in Figure 1, or as shown in Figure 2. It will also be understood that the bunker pan means may be formed as separate flash or evaporator pans or louvers, or as continuous partition devices, in any form of the invention.

Referring now to the embodiment of my invention illustrated in Figure 4, there is shown a fragmentary portion of a refrigerator, or meat treating and storing device 11^c, comprising a

room or compartment 12^c, provided with means, as in the preceding embodiments, for supporting and storing meat or other food (not shown).

As in the preceding embodiments, refrigerating and humidifying coils or pipes 16^c are shown disposed directly in the compartment 12^c. In the present embodiment, however, these pipes are arranged in two banks, that is, an additional layer of pipes 16^d is provided, making a group thicker vertically than the groups shown in the preceding embodiments.

Supplementary humidifying means may be provided like those designated 21 in the first embodiment, if desired, especially if it is found that the system requires more humidification. A 15 bunker pan or partitioning wall may be disposed under the pipes, as in Figure 1 or separate louvers or drip pans 44^c, 45^c and 46^c provided, as in the embodiment of Figure 3. These slope downwardly, as illustrated, and a baffling portion 24^c is desirably provided, extending vertically from the higher side of the pan 46^c and along the outer side of the pipes 16^c and 16^d.

In order to cause the circulating air to pass directly between the coils 16^d and 16^c, rather than completely thereabove, I provide a baffle 25^c, desirably extending from the ceiling 27^c downwardly and toward one side wall to approximately the top of the refrigerating and humidifying means 16^c. The action of this baffle may be supplemented by that of a deflector 29^d, desirably disposed vertically between the baffle 25^c and the adjacent end of the short or upper layer of coils 16^d. This baffle equalizes the flow of air through the layers of coils 16^c and 16^d, and overcomes the natural tendency of an excess of air to pass through the coils at the end where there is only a single layer.

Ceiling deflectors, corresponding with those designated 28 and 29 in Figure 1, may also be employed, if desired, and some or all of the said deflectors may be disposed at an angle, as indicated in Figure 3 by the reference character 29^c.

In the present embodiment, I provide an electric fan 32^c, as in the preceding embodiments, for augmenting the circulation of air up the right side of the box and down through or between cooling pipes, from whence it is discharged downwardly at the left, or center of the box if used in a box of the type shown in Figures 1 and 3, thereby getting a maximum cooling and humidifying effect.

Supplemental humidifying means, not shown, corresponding with those of the preceding embodiments, may be provided if found desirable, and ultra-violet generating means 35^c and 36^c, in the present instance, desirably disposed on the walls, as illustrated, may be provided as in the preceding embodiment.

Referring now to Figure 5, we find a chart 47 which shows the operation of the device in accordance with my invention, as compared with the operation of refrigerators without my inventive features.

In a small walk-in refrigerator, when not using baffles in accordance with my invention, there was difficulty in obtaining the desired relative humidity of approximately 90%. New coils were installed in this refrigerator in an effort to bring the humidity up from approximately 70% to 90%. However, even with spray type humidifiers, we were unable to obtain 90%, the best value being 83%.

There was considerable variation in the humidity during the operation cycle of the com-

pressor, as indicated by the dotted line 48 in Figure 5. There was also difficulty in obtaining consistent temperature as the coils would accumulate ice which interfered with the air circulation.

After the installation of fans and baffles, as previously described, it was possible to increase the back pressure of the refrigeration compressor and thus operate the coils or pipes of 10 the cooling means at somewhat higher temperatures and maintain a more even temperature in the refrigerator. The relative humidity was increased to that indicated by the line 49 of Figure 5, while the variation was reduced.

In a larger walk-in refrigerator there were two cooling coils placed above the usual bunker or drip pan. In operating this refrigerator at 40° F., with the usual gravity circulation, the relative humidity could not be maintained at 20 more than 78%, as indicated by the line 48 in Figure 5. Fans and baffles were installed in accordance with the preceding disclosure and, without making any adjustment of the refrigerating equipment, the temperature dropped 25 about 3° F., from that indicated by the dotted line 51, to that of the full line 52, and the relative humidity increased to an average of about 90% as approximately indicated by the line 49 of Figure 5. After increasing the back pressure of the compressor to raise the temperature of the refrigerant, the box temperature was more uniform and slightly higher and the relative humidity was maintained at a nearly constant value above 90%.

35 The positive circulation of air in a manner to aid natural circulation gives more accurate temperature control regardless of whether the service door is being opened frequently. There is no necessity for condensation of moisture in any part of a box operating in accordance with my invention. While tests show that the air in all parts of the box is in motion, there are no strong blasts over the meat or other food products. The practical beneficial results are 40 indicated by a shrinkage during a storage period of one week of only 1.35% in a 5 ft. x 7 ft. box, and 1.05% in an 8 ft. x 10 ft. box.

It is impractical to maintain a relative humidity as high as 90% by mere gravity circulation of air, because of the necessity for excessively large cooling coils, so that the proposed arrangement of fans and baffles is of great commercial value. By the use of my invention, the meat retains more of its natural juices and value 45 and is, therefore, more palatable. Vegetables retain their crisp freshness for longer periods of time.

It will, therefore be seen, that I have improved the action of refrigerators, whether for 50 tenderizing or storing purposes, by applying fans and/or baffles to make the air circulate positively in a desired manner, that is, in accordance with natural convection currents, prevent wasteful eddy currents, and desirably increase natural circulation, thereby producing extremely high relative humidity while employing cooling coils or pipes of moderate size and degree of refrigeration. I am, therefore, able to convert present low humidity refrigerators into high humidity devices at small expense and with a general improvement in the condition for keeping food products. The advantages obtained by my novel arrangement of fans and/or baffles are:

55 1. The cooling coils are used more efficiently,

thus reducing the difference between coil temperature and air temperature.

2. Any given coil temperature produces a cooler refrigerator than can be obtained without the fans and baffles.

3. Relatively humidity of the air is increased about ten points above that obtainable without the fans and baffles.

4. The cooling coil temperature may be increased without increasing the box temperature.

5. Reduction in power required to operate compressor is more than enough to operate the fans, thus making a more efficient refrigerator.

6. Meat retains bright color longer because of high relative humidity.

7. Vegetables do not wither when stored at high humidity.

8. Loss of weight of meat is reduced and surface drying minimized.

9. The equipment can be applied to all existing refrigerators having overhead coils and independent control of coil temperature.

10. Temperature of refrigerator is made more nearly constant.

11. Rapid circulation of air over coils is secured without causing air blasts over the meat.

12. This combination of fans and baffles will permit a much larger number of retail meat dealers to get optimum results from the use of ultra-violet light in their refrigerators by materially reducing losses due to dehydration and discoloration.

13. Deflectors projecting down from the ceiling at an angle, as shown, will aid in distributing the air uniformly through large coils.

14. Where coils are long, more than one fan may be used over each coil, or an oscillating fan may be used.

15. Prevention of eddy currents in the top of the refrigerator and the possibility of warm air passing above or around the cooling coils to the lower part of the refrigerator.

16. The baffles prevent the air from passing in any direction except down through the cooling coils, the air thus being thoroughly cooled with a minimum of refrigeration.

17. There is no restriction to, or interference with, the natural convection currents in the refrigerator.

18. Because of the moving air passing through the cooling coils instead of around them, the temperature of the refrigerator is brought more nearly to the temperature of the cooling coils and the efficiency of the system is increased.

19. Frosting of coils is reduced or eliminated because of a more positive flow of air through the coils.

20. High humidity may be maintained in the refrigerator because of the more efficient use of the coils, which is equivalent to increasing the cooling surface.

Although preferred embodiments of my invention have been disclosed, it will be understood that modifications may be made within the spirit and scope of the appended claims, and that features of any embodiment may be modified in accordance with the showing in any other embodiment.

I claim:

1. In apparatus for tenderizing and/or storing meat or other food, the combination of a compartment, refrigerating and humidifying means disposed near the top of said compartment, and baffle means between said refrigerating and humidifying means and the top of said compartment

ment and projecting from the latter for causing the air in said compartment to circulate through said refrigerating and humidifying means.

2. In apparatus for tenderizing and/or storing

meat or other food, the combination of a compartment, means for supporting meat therein, refrigerating pipes disposed above said supporting means and spaced from the top of said compartment, humidifying means in said compartment, a bunker pan beneath said pipes, and baffle means, the upper edge of which engages the top of said compartment, disposed above said refrigerating pipes, for causing air to circulate between said pipes for efficient air chilling.

3. In apparatus for tenderizing and/or storing meat or other food, the combination of a compartment, means for supporting meat therein, refrigerating pipes disposed above said supporting means and spaced from the top of said compartment, humidifying means in said compartment,

20 a bunker pan beneath said pipes, and baffles extending longitudinally of the pipes between the same and top of said compartment and engaging the latter, and causing air to circulate between said pipes to effect efficient chilling of the air.

4. In apparatus for tenderizing and/or storing meat or other food, the combination of a compartment, means for supporting meat therein, pipes disposed above said supporting means and spaced from the ceiling of said compartment, hu-

midifying means in said compartment, a bunker pan under said pipes, baffle means between said refrigerating pipes and the top of said compartment, and a deflector projecting down from the ceiling towards said pipes to direct air between the same.

5. In apparatus for tenderizing and/or storing meat or other food, the combination of a compartment, means for supporting meat therein, re-

frigerating pipes disposed above said supporting means and spaced from the top of said compartment, humidifying means in said compartment, a bunker pan under said pipes, baffle means between said refrigerating pipes and the top of said compartment and projecting from the latter, and means for positively circulating air between said pipes to effect efficient air humidifying and chilling.

6. In apparatus for tenderizing and/or storing meat or other food, the combination of a com-

partment, means for supporting meat therein, refrigerating pipes disposed above said supporting means and spaced from the top of said compartment, humidifying means in said compartment, a bunker pan below said pipes, baffle means between said refrigerating pipes and the top of said compartment, and fan means placed in the warm air flue above said pipes and directed toward the baffle means in a substantially horizontal direction, for causing air to circulate over and between said pipes for efficient moistening and chilling.

7. In apparatus for tenderizing and/or storing meat or other food, the combination of a com-

partment, means for supporting meat in said compartment, refrigerating means disposed above said supporting means and spaced from the top of said compartment, humidifying means in said compartment, ultra-violet generating means, and means for causing the air in said compartment to circulate gently over said generating means and more rapidly through said refrigerating and humidifying means.

8. In apparatus for tenderizing and/or stor-

compartment, means for supporting meat therein, refrigerating pipes disposed above said supporting means and spaced from the top of said compartment, humidifying means in said compartment, a bunker pan beneath said pipes, ultra-violet generators beneath said bunker pan, and baffle means between said refrigerating pipes and the top of said compartment, for causing air to circulate between said pipes for efficient air chilling.

9. In apparatus for tenderizing and/or storing meat or other food, the combination of a compartment, means for supporting meat therein, refrigerating pipes disposed above said supporting means and spaced from the top of said compartment, humidifying means in said compartment, a bunker pan beneath said pipes, ultra-violet generators beneath said bunker pan, and baffles extending longitudinally of the pipes between the same and the top of said compartment, and causing air to circulate between said pipes to effect chilling of the air.

10. In apparatus for tenderizing and/or storing meat or other food, the combination of a compartment, means for supporting meat therein, pipes disposed above said supporting means and spaced from the ceiling of said compartment, humidifying means in said compartment, a bunker pan under said pipes, baffle means between said refrigerating pipes and the top of said compartment, ultra-violet generators disposed above said meat-supporting means, and a deflector projecting down from the ceiling towards said pipes to direct air between the same.

11. In apparatus for tenderizing and/or storing meat or other food, the combination of a compartment, means for supporting meat therein, refrigerating pipes disposed above said supporting means and spaced from the top of said compartment, humidifying means in said compartment, a bunker pan under said pipes, baffle means between said refrigerating pipes and the top of said compartment, means for positively circulating air between said pipes to effect efficient air humidifying and chilling, and ultra-violet generators disposed adjacent said bunker pan for sanitizing the meat and circulating air.

12. In apparatus for tenderizing and/or storing meat or other food, the combination of a compartment, means for supporting meat therein, refrigerating pipes disposed above said supporting means and spaced from the top of said compartment, humidifying means in said compartment, a bunker pan means below said pipes, baffle means between said refrigerating pipes and the top of said compartment, fan means placed in the warm air flue above said pipes and directed toward the baffle means in a substantially horizontal direction for causing air to circulate over and between said pipes for efficient moistening

and chilling, and ultra-violet ray generators disposed to directly irradiate the meat.

13. In a walk-in refrigerator with overhead cooling surfaces, the combination of moisture condensing areas, forced air movement directed by baffles and/or deflectors, projecting from the top wall of said refrigerator and restricting the space between said wall and areas, and supplementing thermal convection over said areas, for increasing the moisture content of the air.

14. In a walk-in refrigerator with overhead cooling surfaces, means for rapidly sweeping the cooling surfaces with air moving in the same direction as the natural thermal convection currents and including baffles projecting directly from the top wall of said refrigerator.

15. In a walk-in refrigerator with overhead cooling surfaces, means for moistening the circulating air by rapidly sweeping it in the same direction as the thermal currents over surfaces cooled below the dew point and including simple flat baffles projecting diagonally downward from the top wall of said refrigerator.

16. In a walk-in refrigerator with overhead cooling surfaces, means for preventing wasteful eddy currents comprising baffles extending directly from the ceiling and closing the space between said ceiling and the cold air discharge side of the cooling surfaces.

17. In cooling apparatus of the walk-in type for storing meat or other food, the combination of moisture condensing means, means for supplementing the convection currents, and means for directing said supplemented air currents through the moisture condensing means including baffles sloping diagonally downward directly from the ceiling in the direction of natural convection currents above said condensing means.

18. In a walk-in refrigerator with overhead cooling coils, the combination of moisture condensing means, diagonal air deflecting means thereabove, and means projecting directly from the ceiling for rapidly passing air over the cooling coils and moisture condensing means.

19. In a walk-in refrigerator with overhead cooling and humidifying coils, the combination of a fan and diagonally disposed baffles projecting directly from ceiling to coils and providing means to increase the speed of convection air flow through said coils.

20. In apparatus for tenderizing and/or storing meat or other food, the combination of a compartment, refrigerating means disposed near the top of said compartment, ultra-violet generating means, and means for causing the air in said compartment to circulate gently over said generating means and more rapidly through said refrigerating means.

ARTHUR R. DENNINGTON.
